UNITED STATES PATENT OFFICE.

WILLIAM C. HUSS, OF CINCINNATI, OHIO.

DESIGN FOR A BAR-FIXTURE.

No. 37,609.

Specification for Design.

Patented Oct. 31, 1905.

Application filed May 10, 1905. Serial No. 259,837. Term of patent 7 years.

To all whom it may concern:

Be it known that I, WILLIAM C. HUSS, a citizen of the United States of America, and a resident of Cincinnati, county of Hamilton, State of Ohio, have invented a certain new, original, and ornamental Design for a Bar-Fixture, of which the following is a specification.

I claim—

The ornamental design for a bar-fixture, as shown.

WILLIAM C. HUSS.
